(57) **CLAIM**

The ornamental design for a toy car kit, as shown and described.

DESCRIPTION

FIG. 1 is a perspective view of a toy car of a toy car kit shown separately for ease of illustration;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a perspective view of a track piece of the toy car kit shown separately for ease of illustration;
FIG. 10 is another perspective view thereof;
FIG. 11 is a front elevational view thereof;
FIG. 12 is a rear elevational view thereof;
FIG. 13 is a left side elevational view thereof;
FIG. 14 is a right side elevational view thereof;
FIG. 15 is a top plan view thereof;
FIG. 16 is a bottom plan view thereof; and,
FIG. 17 is a perspective view of the toy car kit shown in use where the toy car is put on a track consisting of a plurality of the track pieces.

The broken lines in the drawings depict portions of the toy car kit that form no part of the claimed design.
